UNITED STATES PATENT OFFICE.

LEONARD D. NILSON, OF WAYZATA, MINNESOTA, ASSIGNOR TO MARQUETTE MANUFACTURING COMPANY, OF ST. PAUL, MINNESOTA.

LIFTING JACK.

Application filed July 26, 1926. Serial No. 125,011.

The object of my invention is to provide a lifting jack specially adapted for use in automobile service work wherein an automobile may be lifted quickly and easily for supporting one end thereof in position where the tire may be removed from the wheel of the automobile.

More particularly it is my object to provide a lifting jack adapted to engage a portion of an automobile spaced only a few inches above the ground and capable of raising the same to a substantial distance above the ground, the parts being very simple, durable, and efficient.

Still a further object is to provide a frame having a curved notched member fixed thereon and a load lifting arm having mechanism thereon and carried thereby for engaging the fixed curved member, the load lifting arm being raised through the engagement of the mechanism carried thereby with the curved member.

Still a further object is to provide a fixed notched sector and a movable lifting arm and mechanism carried by the load lifting arm for engagement with the notched sector, and means for operating the mechanism carried by the load lifting arm for imparting movement to the load lifting arm.

Still a further object is to provide a notched sector and a swinging load lifting arm having a lifting pawl and a locking pawl movable relative to the lifting arm and mounted thereon, the pawls being adapted to engage the notches in the sector in a step by step relation, and an operating handle connected to the lifting pawl whereby operation of the handle will cause the lifting arm to swing relative to the lifting pawl, carrying with it the locking pawl, and after

the locking pawl has been moved from one notch to the next notch, then the lifting pawl itself becomes free and is permitted to be moved while the lifting arm remains fixed and permitting the lifting pawl to assume a position in the next notch where movement of the swinging arm may again be repeated.

Still a further object is to provide a lifting jack wherein movement of the lifting arm is imparted thereto through a connection between the lifting pawl and the swinging arm itself.

Still another object is to provide a control device for reversing the action of the lifting and locking pawls for permitting the load lifting arm to be lowered in a step by step movement so long as the load is upon the lifting arm and thereafter said control mechanism functioning for rendering both of the pawls inoperative and permitting the load lifting arm to assume its normal starting position.

Still a further object is to provide a lifting pawl carrying frame pivotally mounted upon the load lifting arm and capable of pivotal movement relative to the lifting pawl mounted thereon and relative to the lifting arm.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a top plan view of my improved lifting jack with parts shown in section to illustrate the construction.

Figure 2 is a sectional view taken on line 2—2 of Figure 1, parts being broken away.

Figure 3 is a detail view of a portion of the operating handle and the control member mounted thereon.

Figure 4 is a side view of my lifting jack illustrating the load lifting arm in its down position in solid lines and in its raised position in dotted lines.

Figure 5 is a sectional view taken on line 5—5 of Figure 1, illustrating the lifting arm and mechanism carried thereon in its raised position.

Figure 6 is a detail sectional view taken on line 6—6 of Figure 5, illustrating the load lifting head and its connection with the stabilizing arms and load lifting arms.

Figure 7 is a detail view illustrating the locking and lifting pawls in position where both are engaged with the notched sector.

Figure 8 is a similar view with the lifting pawl out of engagement with the notched sector.

Figure 9 is another view illustrating the locking and lifting pawls in another of their

positions with the load lifting arm traveling downward.

Figure 10 is a sectional view taken on line 10-10 of Figure 2; and

5 Figure 11 is a detail sectional view taken on line 11-11 of Figure 2.

In the accompanying drawings, I have used the reference numerals 10 and 12 to indicate a pair of axles upon which my lifting jack is assembled.

10 The axle 10 has a sleeve 14 thereon which has its ends resting against a pair of triangular shaped plates 16 which form a portion of the supporting frame of the lifting jack 15 as will hereinafter be more fully described.

The plates 16 are each formed with openings through which the axles 10 and 12 extend. On the end of the axle 10 beyond the plates 16 I mount short spacing sleeve 18 upon which are journaled wheels 20. The ends of the axle 10 are threaded and nuts 22 are placed thereon for holding the wheels 20 in position and at the same time holding the sleeves 18 and the sleeve 14 in engagement 20 with the frame plates 16. Similar sleeves 18 are mounted upon the ends of the axle 12 and the ends of the axle 12 are also formed with screw threads and receive nuts 22.

25 The upper corner of the plates 16 are connected together by a bolt 24 which has one of its ends screw threaded and receives a nut 26 thereon. The axle 12 and the bolt 24 between the frame plates 16 each have a pair of spacing sleeves 28.

30 Received upon the axle 12 and the bolt 24 and between the spacing sleeves 28, is a curved notched member or sector 30. The notched sector may be formed with ribs 32 for reinforcing purposes and the ends thereof are formed with openings for receiving the bolt 24 and the axle 12.

35 Upon the sleeves 18, mounted upon the axle 12 are journaled wheels 20 similar to the wheels 20 upon the axle 10.

40 45 From the construction of the parts just described, it will be seen that the frame plates 16 are held in spaced apart position and that the notched sector 30 is held therebetween upon the axle 12 and bolt 24. The parts just described may properly be called the supporting frame of my lifting jack.

50 Pivoted to each frame plate 16 upon a pivot bolt or the like 34 is a lifting arm 36. It will be noted that I have provided a pair of lifting arms 36 although a single arm may be used. I have illustrated in the drawings such construction and materials as will enable the lifting jack to be made of sheet iron by stampings although the parts may be made of castings. The lifting arms 36 are spaced apart. The outer or free ends of the lifting arms 36 are connected together by a spindle or the like 38. A load lifting head or member 40 is carried by the spindle 38 and received between the two spaced lift-

ing arms 36 as clearly illustrated in Figure 6 of the drawings. The load lifting head is substantially yoke shaped and has a knurled or roughened head 42 and serves for engaging a portion of an automobile or other vehicle.

55 Spacing sleeves or washers 44 are interposed between the sides of the member 40 and the arms 36. A sleeve 46 is also provided upon the spindle 38 and is received between the two arms of the member 40 as clearly illustrated in Figure 6 of the drawings.

A pair of stabilizing arms 48 are connected to a spindle 50 which is journaled 80 in the member 40 above the spindle 38. Washers or the like 52 are interposed between the stabilizing arms 48 and the member 40. The free ends of the stabilizing arms 48 are pivotally connected to the sleeves 28 upon the bolt 24.

90 From the construction of the parts just described it will be seen that the lifting arms 36 and the stabilizing arms 48 together with the frame plates 16 to which they are pivotally connected and the load lifting head 40 form a parallelogram thus maintaining the member 40 in a substantially vertical position during its movement. The member 40 may have an extension head 54 pivotally 95 connected thereto and adapted when in one position to swing upon and rest upon the roughened portion 42 of the member 40. The position just described is clearly illustrated in Figure 2 of the drawings.

100 The extension head 54 is pivotally supported by the pivot member 56, journaled in the ears 58 formed on the member 40 itself. The extension head 54 may be moved through substantially ninety degrees and when in this position will not interfere with the free use of the member 40 itself and particularly the roughened surface 42 thereof.

110 The extension head 54 may have a stop thereon for engagement with a portion of the member 40 for holding the extension head 54 in its substantially horizontal position or inoperative position. The extension head is only necessary when it is desired to engage a member that the original starting position thereof is substantially high above the ground and where the "lift" is comparatively high.

115 The two spaced members 36 which constitute the lifting arms are connected together intermediate of their ends by a transverse bolt or pivot member 62. Pivotally mounted upon the bolt 62 and between the two arms 36 are a pair of triangular shaped carrying frame plates 64. The plates 64 are 120 in turn connected together by a separate pivot member or bolt 66. Mounted upon the bolt or pivot 62 is a locking pawl 68. The locking pawl 68 is received between the two carrying frame plates 64 and is adapted to 125

130

engage the notched sector 30 as clearly illustrated in Figure 2 of the drawings.

The locking pawl 68 is formed with a cam surface extension 70, the purpose of which will be hereinafter more fully set forth.

The locking pawl 68 is mounted upon the pivot bolt 62 and is capable of movement in dependent of the movement of the pawl carrying frame plates 64. Between the two carrying frame plates 64 and pivotally mounted upon the pivot bolt 66 is a lifting pawl 72 adapted to engage the notches 74 of the notched sector 30.

From the construction of the parts just described, it will be seen that pivotal movement of the two carrying plates 64 upon the bolt 62 will cause the lifting pawl to be carried therewith.

The lifting pawl 72 is formed with a cam extension 76, the purpose of which will hereinafter be more fully set forth.

The locking pawl 68 and the lifting pawl 72 are connected together by a spring 78. The spring 78 has one of its ends anchored to an extension 80 upon the lifting pawl 72 and has its other end extended through an opening 82 formed in the locking pawl itself as clearly illustrated in Figure 2 of the drawings. The spring 78 tends to hold the locking and lifting pawls always in engagement with the notched sector 30.

An operating handle 84 is pivotally mounted upon the sleeves 28 which are mounted upon the axle 12. The operating handle 84 is formed of strap material connected together at one end by a hand engaging piece 86. The side members of the handle 84 each have short plates 88 connected thereto in any suitable manner, preferably by rivets 90. The plates 88 have a pivot bolt 92 journaled therein to which are fixed a pair of spaced pull bars 94. The pull bars in turn are pivotally connected to the pivot bolt 96, journaled in the two spaced carrying frame plates 64. The pull bars 94 serve as a connection between the operating handle and the load lifting arm through the medium of the carrying frame plates 64.

50 *Practical operation for raising the lifting arms.*

I will now describe the operation of my lifting jack for having it move from the position shown in solid lines in Figure 4 to the position shown in dotted lines. In Figure 2 I have shown the locking pawl 68 in engagement with the bottom notch 74 and the lifting pawl in engagement with another of the notches 74 above the notch that the locking pawl is in. In this position the operating handle 84 is moved in a downward direction as indicated by the arrow 98 which causes the pull bars 94 to move in the direction indicated by the arrow 100. This movement in

turn pulls the carrying frame forwardly and causes it to pivot around the pivot point or bolt 66 of the lifting pawl 72. The carrying frame 64 pivots in the direction indicated by the arrow 102. The result of this movement is to carry with it the lifting arms 36. The lifting arms 36 being fixed so far as the locking pawl is concerned causes the locking pawl 68 to be withdrawn from the notched sector and as soon as the locking pawl 68 is out of the notch it is in in Figure 2 then the spring 78 immediately causes it to be pulled towards the lifting pawl 72 and this pulls the locking pawl into the notch just below the notch that the lifting pawl is in.

The locking pawl then holds the load lifting arm 36 in its "stepped up" position. The operating handle is then moved upwardly a short distance. This movement imparts a rearward movement to the pull bars 94 in a direction indicated by the arrows 104. This in turn swings the carrying plates 64 upon the pivot bolt 62 and at the same time carries the lifting pawl and pulls it out of engagement with one of the notches 74 of the sector 30. The spring 78 tends to hold the lifting pawl always in engagement with the sector itself and as soon as the carrying frame plates 64 have been swung upon their pivot 62 a sufficient distance for the lifting pawl to clear the one notch that the lifting pawl was originally in then the spring functions and returns the lifting pawl into engagement with the next above notch. The lifting pawl is raised by the carrying frame 64 to a position where it may enter the next above notch.

While the carrying frame plates 64 are being moved for permitting the lifting pawl to assume the next above notch, the locking pawl 68 holds the lifting arms 36 in a fixed position relative to the sector 30. After the lifting pawl has assumed the next above notch then the handle 84 is again moved downward in the direction indicated by the arrow 98. The carrying frame plates 64 are then moved again upon the pivot bolt 66 as an axis for imparting a lifting swinging movement to the lifting arms 36 and movement of the locking pawl from one notch to the next above notch. The action is repeated and the lifting arms are moved upwardly in a step by step movement. It will be noted that the lifting arms carry practically all the mechanism used for lifting them and for holding them in their lifted position. The carrying frame plates 64 serve as the connection by which the operating handle transmits upward movement to the lifting arms. The carrying frame at the same time serves as the means for permitting the lifting pawl to advance step by step for permitting it to assume the necessary position whereby the lifting arms themselves may then be raised.

It may further be mentioned that during upward movement of the lifting arms 36 the fulcrum or pivot point of the carrying frame 64 is the pivot 66 and when the lifting pawl 5 is moved from one position to another, then the pivot point or fulcrum of the carrying frame 64 is the pivot bolt 62.

Operation for lowering lifting arms.

- 10 I will now describe in detail the mechanism for controlling the locking and lifting pawls for permitting them to operate in such manner as to permit the load to be lowered in a step by step downward movement 15 through the operation of the operating handle.

Mounted upon the sleeve 46 is a cam engaging lever 106 which has cables 108 fastened to a yoke member 110 which in turn is fixed to the free end of the lever 106. The lever 106 is designed to engage the cam extension 70 upon the locking pawl 68 and the cam extension 76 upon the lifting pawl 72. The cables 108 extend around pulley wheels 112 which are mounted upon the two lifting arms 36. The cables then extend around pulley wheels 114 mounted upon the pivot bolts 34 of the lifting arms 36. The cables then extend around pulley wheels 30 mounted upon the sleeves 28 on the axle 12 whereby the cables extend around the pulleys at the pivot point or connection between the operating handle and the supporting frame. The purpose of providing the arrangement of pulleys as here illustrated is to permit free use of the operating handle without in any way affecting the lever 106 or applying undue tension upon the lever 106. The cables 108 have coil springs 116 connected thereto which in turn are connected to wires 118. The wires 118 project along the sides of the operating handle 84 and are connected to a pivoted hand piece 120. The hand piece 120 is pivotally mounted upon the operating handle 84 as at 122.

The lever 106 does not affect the lifting and locking pawls during upward movement of the lifting jack and only functions when the lifting jack is being moved downwardly and in order to cause it to function, it is necessary to swing the hand piece 120 from its solid line position in Figure 3 to its dotted line position at which time the springs 116 will be placed under tension causing a downward pushing movement of the lever 106 against the cam extensions 70 and 76 during operation of the lifting and locking pawls.

60 The hand piece 120 and the connection of the wire 118 therewith is of such nature as to cause the hand piece to assume a passed over center position when the hand piece is in the position shown in dotted lines in Figure 3. During the down movement of the lifting jack and while a load is resting upon

the load member 40, the lever 106 operates as I will now describe.

Assuming that the starting position for moving the load downward is the position shown in Figure 5 of the drawings, the lifting pawl 72 is then in engagement with one of the notches in the sector 30. The lever 120 is moved to dotted line position as shown in Figure 3 of the drawings. The lever 106 then engages the cam extension 76 75 as well as the cam extension 70 on the locking pawl 68. Upward movement of the operating handle 84 will impart movement to the pull bars in the direction indicated by the arrow 124 in Figure 5 of the drawings.

This upward movement will cause the carrying plates 64 to swing about the pivot 66 and the engagement of the lever 106 with the cam extension 70 will render the coil spring 78 inoperative and the locking pawl 68 will be held out of engagement with the notched sector 30. Further movement of the carrying frame 64 will cause the cam extension 70 to free itself from the lever 106 as 90 clearly shown in Figure 7 of the drawings, the lever 106 being held in its raised position by the cam extension 76 on the lifting pawl 72.

As soon as the extension 70 is released 95 from contact with the lever 106, then the coil spring 78 immediately functions for pulling the locking pawl into engagement with the notched sector 30 and the parts then assume the position shown in Figure 7 100 of the drawings.

After the locking pawl 68 has assumed the position shown in Figure 7 of the drawings, then a slight amount of upward movement of the operating handle pulls the lifting pawl away from the notched sector 30 and then the engagement of the lever 106 with the cam extension 76 pushes the lifting pawl out of engagement with the notched sector and holds it out of engagement. 110 After the lifting pawl 72 has been moved from the position shown in Figure 7 of the drawings to the position shown in Figure 8 of the drawings, then downward movement of the operating handle imparts movement 115 to the pull bars 94 in the direction indicated by the arrows 126. This movement causes the carrying frame 64 to pivot upon the pivot bolt 62 throwing the lifting pawl downwardly. As the lifting pawl and carrying frame 64 are moved relative to the pivot bolt 62, the engagement of the lever 106 with the extension 76 is discontinued 120 and then the coil spring 78 functions for immediately forcing the lifting pawl into the notch just below the notch that it previously occupied. The engagement of the lever 106 with the cam extension 76 remains until after the downward movement of the lifting pawl is of sufficient distance so as to 130

pass over the upper edge of this notch and this, of course, insures the lifting pawl to assume the notch next below the notch that it was originally in.

- 5 Continued movement of the operating handle 84 and the movement of the pull bars in the direction indicated by the arrows 126 releases the locking pawl 68 and causes the cam extension 70 thereof to engage with 70
10 the lever 106, thus throwing the locking pawl outwardly and away from the notched sector 30, the lifting pawl then being in engagement with the notched sector 30.

As soon as the locking pawl 68 has been 15 disengaged from the notched sector 30 and as soon as the cam extension 70 disengages the lever 106, then the spring 78 functions for again pulling the locking pawl into the engagement with the next below notch. The 20 lever 106 functions for holding the coil spring 78 inoperative while the locking pawl is moved to assume the next below position and while the lifting pawl is moved to assume the next below position. The engagement of the 25 lever 106 with the locking pawl 68 and lifting pawl 72 is of sufficient length to insure a sufficient movement of the pawls themselves to insure their engagement with the next below notch. The action just referred to is 30 repeated and the load is thereby lowered in a step by step movement.

Instant release operation.

The load itself upon the load lifting arm 35 prevents the lever 106 from throwing both the locking and lifting pawls out of engagement with the notched sector. The load, of course, is sufficient to overcome the tension of the coil springs 116.

- 40 As soon as the load is released from the load lifting arm then the coil springs 116 are of sufficient strength to cause the lever 106 to engage both of the pawls and throw them away from the notched sector to the position 45 shown in dotted lines in Figure 5, at which time, the entire lifting arm and mechanism carried thereby will drop to its original starting position.

It will be noted that one of the advantages 50 of my lifting jack resides in the mounting of the entire lifting mechanism itself upon the load lifting arm and carrying it with the load lifting arm during either the upward or downward movement of the load lifting arm.

Another advantage resides in the arrangement whereby the load itself insures engagement of the locking and lifting pawls with the notched sector during downward movement 55 and as soon as the load is no longer supported upon the lifting arm, then the control mechanism, particularly the coil springs 116, are of sufficient strength to push the lever 106 against the locking and lifting pawls for causing them to free themselves

from the notched sector 30 and permitting the lifting arms and mechanism carried thereon to drop to its starting position. The lifting arms swing upon their pivots and always retain the lifting and locking pawls 70 in position where they will engage the sector even though the lifting and locking pawls themselves are capable of movement relative to the lifting arms.

Some changes may be made in the construction and arrangement of the various parts of my invention, without departing from the real spirit and purpose of my invention, and it is my intention to cover by 75 my claims any modified forms of structure or use of mechanical equivalents, which may be reasonably included within their scope.

I claim as my invention:

1. A lifting jack comprising a supporting frame, a notched sector fixed relative to said frame, a pivoted load lifting arm, a pawl carrying frame pivoted to said arm and carried therewith, a lifting pawl pivoted to said carrying frame at a point spaced from the pivot point of said carrying frame and engageable with said sector and means connected to said carrying frame for imparting movement to said lifting arm.

2. A lifting jack comprising a supporting frame, a notched sector fixed relative to said frame, a pivoted load lifting arm, a pawl carrying frame mounted on and movable relative to said arm and carried therewith, a lifting pawl pivoted to said carrying frame at a point spaced from the connection between said lifting arm and said carrying frame and engageable with said sector, and means connected to said carrying frame for imparting movement to said lifting arm.

3. A lifting jack comprising a supporting frame, a notched sector fixed relative to said frame, a pivoted load lifting arm, a pawl carrying frame pivoted to said arm and carried therewith, a lifting pawl pivoted to said carrying frame at a point spaced from the pivot point of said carrying frame and engageable with said sector, means connected to said carrying frame for imparting movement to said lifting arm, and a locking pawl pivoted to said arm and carried thereon for engaging the notched sector and locking the arm against movement in one direction.

4. A lifting jack comprising a supporting frame, a notched sector fixed relative to said frame, a pivoted load lifting arm, a pawl carrying frame pivoted to said arm and carried therewith, a lifting pawl pivoted to said carrying frame at a point spaced from the pivot point of said carrying frame and engageable with said sector, means connected to said carrying frame for imparting movement to said lifting arm, and a locking pawl pivoted to said arm and carried thereon for engaging the notched sector and locking the arm against movement in one direction, and

means for rendering the locking pawl inoperative.

5. A lifting jack comprising a supporting frame, a notched sector fixed relative to said frame, a pivoted load lifting arm, a pawl carrying frame pivoted to said arm and carried therewith, a lifting pawl pivoted to said carrying frame at a point spaced from the pivot point of said carrying frame and engageable with said sector, an operating handle, a pull bar connected to said handle at one end and to said carrying frame at its other end whereby movement of said handle will impart movement to said carrying frame.

6. A lifting jack comprising a supporting frame, a notched sector fixed relative to said frame, a pivoted load lifting arm, a pawl carrying frame pivoted to said arm and carried therewith, a lifting pawl pivoted to said carrying frame at a point spaced from the pivot point of said carrying frame and engageable with said sector, an operating handle operatively connected to said carrying frame for moving it, said carrying frame when being moved swinging around the pivot point of the lifting pawl as an axis and raising the outer end of the lifting arm.

7. A lifting jack comprising a supporting frame, a notched sector fixed relative to said frame, a pivoted load lifting arm, a pawl carrying frame pivoted to said arm and carried therewith, a lifting pawl pivoted to said carrying frame at a point spaced from the pivot point of said carrying frame and engageable with said sector, an operating handle operatively connected to said carrying frame for moving it, said carrying frame when being moved swinging around the pivot point of the lifting pawl as an axis and raising the outer end of the lifting arm, and a locking pawl movable with the lifting arm for engaging the sector after the carrying frame has moved around the pivot point of the lifting pawl as an axis for freeing the carrying frame and permitting it to swing relative to the lifting arm, carrying with it the lifting pawl.

8. A lifting jack comprising a supporting frame, a notched sector fixed relative to said supporting frame, a pivoted load lifting arm on said supporting frame, a pawl carrying frame pivotally carried by said lifting arm and movable therewith, a lifting pawl on said carrying frame for engaging the notched sector when the arm is being lifted and for holding the arm in its lifted position, means in connection with said lifting arm, through said pawl carrying frame for moving said lifting arm, a load engaging head pivoted to the free end of the load lifting arm and a stabilizer arm pivotally connected to said head and said supporting frame.

9. A lifting jack comprising a supporting frame, a notched sector fixed relative to said

frame, a pivoted load lifting arm, a pawl carrying frame pivoted to said arm and carried therewith, a lifting pawl pivoted to said carrying frame at a point spaced from the pivot point of said carrying frame and engageable with said sector, an operating handle operatively connected to said carrying frame for moving it, said carrying frame when being moved swinging around the pivot point of the lifting pawl as an axis and raising the outer end of the lifting arm, a load engaging head pivoted to the free end of said load lifting arm and means for maintaining the load engaging head in vertical position during movement of the lifting arm.

10. A lifting jack comprising a supporting frame, a notched sector fixed relative to said frame, a pivoted load lifting arm, a pawl carrying frame pivoted to said arm and carried therewith, a lifting pawl pivoted to said carrying frame at a point spaced from the pivot point of said carrying frame and engageable with said sector, an operating handle operatively connected to said carrying frame for moving it, said carrying frame when being moved swinging around the pivot point of the lifting pawl as an axis and raising the outer end of the lifting arm, and a locking pawl movable with the lifting arm for engaging the sector after the carrying frame has moved around the pivot point of the lifting pawl as an axis for freeing the carrying frame and permitting it to swing relative to the lifting arm, carrying with it the lifting pawl and a spring for connecting said locking and lifting pawls together.

11. A lifting jack comprising a wheel mounted frame, a curved member having a series of notches therein, a swinging load lifting arm pivoted on said frame, a lifting pawl and a locking pawl operatively connected to said arm and carried thereby, swinging means for moving the pivot point of said lifting pawl relative to said lifting arm, said pawls adapted to engage said notches in step by step relation, an operating handle operatively connected to said swinging means whereby operation of the handle will cause the arm to swing relative to said lifting pawl carrying with it the locking pawl and pulling it from one notch to the next notch for locking the arm in its moved position, said lifting pawl, after the locking pawl has moved, being free to move while the lifting arm remains fixed for assuming a position in the next notch when the action of swinging the arm may be repeated.

12. A lifting jack comprising a supporting frame, a notched sector fixed relative to said supporting frame, a pivoted load lifting arm on said supporting frame, a pawl carrying frame supported on said load lifting arm and carried thereby, a lifting pawl pivoted on said pawl carrying frame and engageable

with said notched sector and means for imparting movement to said pawl carrying frame relative to said lifting arm.

13. A lifting jack comprising a wheel 5 mounted frame, a curved member having a series of notches therein, a swinging load lifting arm pivoted on said frame, a lifting pawl and a locking pawl operatively connected to said arm and carried thereby, said 10 pawls adapted to engage said notches in step by step relation for upward movement, an operating handle operatively connected to said lifting pawl whereby operation of the handle will cause the arm to swing relative 15 to said lifting pawl carrying with it the locking pawl and pulling it from one notch to the next notch for locking the arm in its moved position, said lifting pawl, after the locking pawl has moved, being free to move 20 while the lifting arm remains fixed for assuming a position in the next notch where the action of swinging the arm may be repeated.

14. A lifting jack comprising a wheel 25 mounted frame, a curved member having a series of notches therein, a swinging load lifting arm pivoted on said frame, a lifting pawl and a locking pawl operatively connected to said arm and carried thereby, said 30 pawls adapted to engage said notches in step by step relation for upward movement, an operating handle operatively connected to said lifting pawl whereby operation of the handle will cause the arm to swing relative 35 to said lifting pawl carrying with it the locking pawl and pulling it from one notch to the next notch for locking the arm in its moved position, said lifting pawl, after the locking pawl has moved, being free to move 40 while the lifting arm remains fixed for assuming a position in the next notch where the action of swinging the arm may be repeated and control means for reversing the 45 action of said pawls and permitting the lifting arm to be lowered in a step by step movement.

15. A lifting jack comprising a wheel mounted frame, a curved member having a series of notches therein, a swinging load 50 lifting arm pivoted on said frame, a lifting pawl and a locking pawl operatively connected to said arm and carried thereby, said pawls adapted to engage said notches in step by step relation for upward movement, 55 an operating handle operatively connected to said lifting pawl whereby operation of the handle will cause the arm to swing relative to said lifting pawl carrying with it the locking pawl and pulling it from one notch 60 to the next notch for locking the arm in its moved position, said lifting pawl, after the locking pawl has moved, being free to move while the lifting arm remains fixed for assuming a position in the next notch where 65 the action of swinging the arm may be re-

peated and control means for reversing the action of said pawls and permitting the lifting arm to be lowered in a step by step movement, so long as the load is upon the load lifting arm.

16. A lifting jack comprising a wheel 70 mounted frame, a curved member having a series of notches therein, a swinging load lifting arm pivoted on said frame, a lifting pawl and a locking pawl operatively connected to said arm and carried thereby, said 75 pawls adapted to engage said notches in step by step relation for upward movement, an operating handle operatively connected to said lifting pawl whereby operation of the 80 handle will cause the arm to swing relative to said lifting pawl carrying with it the locking pawl and pulling it from one notch to the next notch for locking the arm in its 85 moved position, said lifting pawl, after the locking pawl has moved, being free to move while the lifting arm remains fixed for assuming a position in the next notch where the action of swinging the arm may be repeated and control means for reversing the 90 action of said pawls and permitting the lifting arm to be lowered in a step by step movement, said control means including spring means for holding both of said pawls out 95 of engagement with the notched member when the load upon the load lifting arm is released.

17. A lifting jack comprising a wheel 100 mounted frame, a curved member having a series of notches therein, a swinging load lifting arm pivoted on said frame, a lifting pawl and a locking pawl operatively connected to said arm and carried thereby, said 105 pawls adapted to engage said notches in step by step relation for upward movement, an operating handle operatively connected to said lifting pawl whereby operation of the handle will cause the arm to swing relative to said lifting pawl carrying with it the locking pawl and pulling it from one notch 110 to the next notch for locking the arm in its moved position, said lifting pawl, after the locking pawl has moved, being free to move while the lifting arm remains fixed for assuming a position in the next notch where 115 the action of swinging the arm may be repeated and control means for reversing the action of said pawls and permitting the lifting arm to be lowered in a step by step movement, so long as the load is upon the load 120 lifting arm, said control means after the load upon the load lifting arm is released, functioning for holding both of said pawls out of engagement with said notched member and permitting the lifting arm to drop.

18. A lifting jack comprising a wheel 125 mounted frame, a curved member having a series of notches therein, a swinging load lifting arm pivoted on said frame, a pawl carrying frame pivotally supported upon 130

said arm, a lifting pawl on said carrying frame at a point spaced from the pivotal connection between said carrying frame and said arm, a locking pawl on said arm, said pawls being adapted to engage said notches and move therein in a step by step movement, an operating device for moving said pawl carrying frame with the lifting pawl as the axis for such movement, such movement imparting a lifting movement to said arm, said locking pawl holding the arm in its moved position and permitting the pawl carrying frame and lifting pawl thereon to pivot relative to said arm and allow the lifting pawl to assume a position in another of the notches.

19. A lifting jack comprising a frame, a curved member having a series of notches therein, a pivoted load lifting arm, a pawl carrying frame and a holding pawl pivoted on said load lifting arm, a lifting pawl pivoted to said pawl carrying frame, an operating handle operatively connected to said pawl carrying frame for causing pivotal movement of the pawl carrying frame relative to the load lifting arm whereby the lifting pawl is moved to engage one of the notches in said curved member when the handle is moved in one direction and for causing pivotal movement of the pawl carrying frame about the lifting pawl as a pivot when the handle is moved in the other direction for raising the load lifting arm.

20. A lifting jack comprising a frame, a curved member having a series of notches therein, a pivoted load lifting arm, a pawl carrying frame and a holding pawl pivoted on said load lifting arm, a lifting pawl pivoted to said pawl carrying frame, an operating handle operatively connected to said pawl carrying frame for causing pivotal movement of the pawl carrying frame relative to the load lifting arm whereby the lifting pawl is moved to engage one of the notches in said curved member when the handle is moved in one direction and for causing pivotal movement of the pawl carrying frame about the lifting pawl as a pivot when the handle is moved in the other direction for raising the load lifting arm and moving the holding pawl to position for engaging the next above notch, spring means for holding said pawls in engagement with the curved member and control means for reversing the action of said pawls and permitting the lifting arm to be lowered in a step by step movement.

21. A lifting jack comprising a wheel mounted frame, a curved member having a series of notches therein, a swinging load lifting arm pivoted on said frame, a lifting pawl and a locking pawl operatively connected to said arm and carried thereby, said pawls adapted to engage said notches in step by step relation, an operating handle opera-

tively connected to said lifting pawl whereby operation of the handle will cause the arm to swing relative to said lifting pawl carrying with it the locking pawl and pulling it from one notch to the next notch for locking the arm in its moved position, and a common spring for holding said pawls in engagement with the curved member, said lifting pawl, after the locking pawl has moved, being free to move while the lifting arm remains fixed for assuming a position in the next notch where the action of swinging the arm may be repeated.

22. A lifting jack comprising a frame, a curved member having a series of notches therein, a pivoted load lifting arm, a pawl carrying frame and a holding pawl pivoted on said load lifting arm, a lifting pawl pivoted to said pawl carrying frame, an operating handle operatively connected to said pawl carrying frame for causing pivotal movement of the pawl carrying frame relative to the load lifting arm whereby the lifting pawl is moved to engage one of the notches in said curved member when the handle is moved in one direction and for causing pivotal movement of the pawl carrying frame about the lifting pawl as a pivot when the handle is moved in the other direction for raising the load lifting arm and moving the holding pawl to position for engaging the next above notch, means for reversing the action of said pawls for lowering the load lifting arm, said means comprising a lever pivoted to the load lifting arm, and projections on said pawls designed to be engaged by said lever for maintaining the pawls disengaged from the notches in said curved member.

23. A lifting jack comprising a frame, a curved member having a series of notches therein, a pivoted load lifting arm, a pawl carrying frame and a holding pawl pivoted on said load lifting arm, a lifting pawl pivoted to said pawl carrying frame, an operating handle operatively connected to said pawl carrying frame for causing pivotal movement of the pawl carrying frame relative to the load lifting arm whereby the lifting pawl is moved to engage one of the notches in said curved member when the handle is moved in one direction and for causing pivotal movement of the pawl carrying frame about the lifting pawl as a pivot when the handle is moved in the other direction for raising the load lifting arm and moving the holding pawl to position for engaging the next above notch, spring means for holding said pawls in engagement with the curved member and means for rendering said spring means inoperative for lowering the load lifting arm, said means comprising a lever pivoted to the load lifting arm, and projections on said pawls designed to be engaged by said lever

for maintaining the pawls disengaged from the notches in said curved member.

24. A lifting jack comprising a frame, a curved member having a series of notches therein, a pivoted load lifting arm, a pawl carrying frame and a holding pawl pivoted on said load lifting arm, a lifting pawl pivoted to said pawl carrying frame, means for actuating said pawl carrying frame whereby said pawls are caused to successively engage the notches in said curved member with a step by step movement and said load lifting arm is raised, a reversing control device for engaging said pawls for reversing the direction of movement of the load lifting arm.

25. A lifting jack comprising a frame, a curved member having a series of notches therein, a pivoted load lifting arm, a pawl carrying frame and a holding pawl pivoted on said load lifting arm, a lifting pawl pivoted to said pawl carrying frame, means for actuating said pawl carrying frame whereby said pawls are caused to successively engage the notches in said curved member with a step by step movement and said load lifting arm is raised, resilient means for causing said pawls to engage said notches, a reversing control lever pivoted on said load lifting arm, cams on said pawls, means for causing said lever to resiliently engage said cams for moving said pawls for disengaging them from said notches.

26. A lifting jack comprising a frame, a curved member having a series of notches therein, a pivoted load lifting arm, a pawl carrying frame and a holding pawl pivoted on said load lifting arm, a lifting pawl pivoted to said pawl carrying frame, means for actuating said pawl carrying frame whereby said pawls are caused to successively engage the notches in said curved member with a step by step movement and

said load lifting arm is raised, resilient means for causing said pawls to engage said notches, a reversing control lever pivoted on said load lifting arm, cams on said pawls, means for causing said lever to resiliently engage said cams for moving said pawls for disengaging them from said notches, the cam on either of said pawls serving to disengage said lever from the cam on the other pawl thereby allowing said other pawl to engage a notch in the curved member. 55

27. A jack comprising a notched member, a load lifting arm provided with a pawl carrying frame, said load lifting arm and said pawl carrying frame being provided with pawls, means for causing said pawls to engage the notched member, cams on said pawls, a lever for engaging said cams for rendering said means inoperative, movement of said pawl carrying frame in one direction causing the cam on one of said pawls 60 to disengage said lever from the cam on the other pawl whereby said other pawl is free to engage said notched member and vice versa. 65

28. A jack comprising a notched member, 70 a pawl frame having a pair of pawls pivoted thereto for coacting with said notched member, spring means for causing such coaction, a load lifting arm carried by said pawl frame, means for rocking said pawl frame whereby said pawls will engage said notched member in a step by step movement, a reversing means for said pawls comprising a lever, for rendering said spring means inoperative, cams on said pawls the rocking movement of said pawl frame causing the cam on one of said pawls to engage the lever and cause its disengagement from the cam on the other pawl for allowing said other pawl to engage said notched member 85 and vice versa.

Des Moines, Iowa, June 30, 1926.

LEONARD D. NILSON.
